UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF NEW JERSEY.

TYPE-WRITING MACHINE.

882,657

Specification of Letters Patent. Patented Jan. 24, 1911.

Application filed October 29, 1909. Serial No. 525,294.

To all whom it may concern:

Be it known that I, CORNELIUS B. CORCORAN, a citizen of the United States, residing in the borough of Bronx, city of New York, in the county of New York and State of New York, have invented certain new and useful Improvements in Type-Writing Machines, of which the following is a specification.

10 This invention relates to paper-guiding devices for the platens of typewriting machines, the principal object being to enable the operator to write conveniently on small labels, cards, etc., and more particularly to 15 enable him to cover the entire label with writing, and also to enable him to see the entire line of writing, as it progresses.

I employ a pair of transparent paper-guiding fingers on opposite sides of and 20 close to the printing point, said fingers being yieldingly urged against the paper to hold it against the platen, the type striking between said fingers. The platen and paper are slidable longitudinally, while the paper 25 holding fingers remain stationary. Said fingers are also shiftable with the platen and paper for upper and lower case positions, so that the paper will always be engaged by them.

30 In the accompanying drawings, Figure 1 is a perspective view, showing one embodiment of my invention applied to the Underwood type of front strike writing machine. Fig. 2 is a detail rear view, partly broken 35 away to show the construction. Fig. 3 is an edge view, partly in cross-section, showing the platen in normal position to print lower case characters. Fig. 4 is a similar view, showing the platen and paper-holding mechanism shifted to permit the imprint of upper case characters.

The frame A of the typewriter is provided with a cross-bar 1, to which is secured a type-bar segment 2, in which the type bars 45 3 carrying the upper and lower case type 7 are pivoted. A platen 4 is rotatably mounted in a platen frame 6, and lies in the path of the type 7, the platen frame being provided with the usual paper-feeding rolls 8 50 engaging the under surface of the platen 4, said platen and platen frame being shiftable up and down by a rocking frame including a pair of elbow levers 9 connected by a shifting rail 10, whereon rides a wheel 55 11 of the platen frame 6.

The rocking frame is swung from the position shown in Fig. 3, to that shown in Fig. 4, by depressing a shift key lever 12 fulcrumed at 13, which lever operates an arm 14 engaging the rocking frame to effect 6 the case-shifting movement of the platen, whereby to effect the writing of upper or lower case characters as desired.

A ribbon vibrator 15 is interposed between the type 7 and the platen 4, and includes a vertically slidable post 16. A vibrating lever 17 fulcrumed to a fixture 18 projecting from the shifting rail 10 has one end connected to the vibrator post 16, the opposite end of the lever 17, carrying a stud 19 70 receivable in a slotted arm 20 mounted on a table 21, horizontally reciprocable to vibrate the ribbon into the path of the type 7 as the latter is brought to the printing point.

The paper-holding mechanism includes a carrier 22, preferably mounted to slide vertically, in the cross bar 1 of the frame of the machine behind the segment 2, on which carrier are mounted upwardly projecting arms 23, whose free ends have secured thereto, paper-holding and guiding fingers 24, preferably of horn, celluloid or other transparent material, and located on opposite sides of the printing point, between the ribbon vibrator and the platen, the fingers being spaced apart from each other sufficiently to allow the type 7 to strike the label held thereby against the platen. The arms are preferably metallic, and (being opaque) 80 terminate below the printing line, so as not to obscure the writing, the transparent fingers being secured to the upper ends of such arms at points below the printing line.

Those portions of the fingers which engage the label are smooth to oppose no resistance to the letter-spacing travel of the platen and label, the latter shifting relative to the fingers, which, while holding the label against the platen, do not press so tightly 100 as to overcome its frictional adherence to the platen, but rather, maintain such adherence in the line-spacing as well as in the letter-spacing throw of the platen.

The entire surface of the label can be utilized for printing. Every portion of the label along the printing line is in sight, owing to the use of transparent paper-holding fingers 24.

When printing a label, the latter is in- 110

serted downwardly in front of the platen and between the latter and the paper-holding mechanism, the upper ends of the fingers being slightly beveled, as shown in Figs. 3 and 4, to permit the insertion of the label, and the fingers are preferably curved to conform to the contour of the platen.

The paper-holding devices, though unconnected with the platen, follow the platen when the latter is shifted, because of their connection with the platen-shifting mechanism, effected by the provision of a tongue 25 projecting from the carrier 16, the free end of the tongue loosely received in an eye 26 on the shifting rail 10, so that the operation of the shift key lever 12 to shift the platen 4 from lower to upper case position or vice versa will cause the shifting rail 10 to slide the carrier 22, and the paper-holding finger 23 mounted thereon, vertically up or down, simultaneously with the platen, the paper-holding devices hence occupying the same relation to the platen in either its upper or lower case positions.

25 The carrier 22 may be provided with shoulders 27 to engage the cross-bar 1 and segment 2 to arrest the carrier when the platen drops to lower-case position. The carrier 22 may be also be provided with open 30 seats 28, to removably receive pintles 29 carried by the lower ends of the arms 23, whereby the latter are detachably hinged to the carrier, to permit their removal if desired when the operator is writing on sheets 35 of ordinary size which can be held by the usual paper fingers.

Arms 23 and fingers 24 are urged toward the platen preferably by leaf springs 30 mounted on and extending longitudinally of 40 the respective arms 23, the lower free ends of the springs 30 having beads or detents 31 received in recesses 32 formed exteriorly of the seats 28 to lock the arms and fingers 45 yieldingly to the carrier 22, the springs being separated from the arms 23 and hence placed under tension when pressing them down over the seats 28, which occupy positions between the springs 30 and the arms 23.

50 Labels of any shape and of various sizes are readily introduced between the paper-holding devices and platen and may be partially or entirely covered with writing as desired, the paper-holding fingers covering 55 and holding the label on opposite sides of the printing point, but permitting the writing to be scanned, owing to the transparent material of which the fingers are composed.

It will be seen that the paper is maintained against the platen at the shifting printing point, by the transparent spring actuated fingers which extend across the printing point on opposite sides of the printing point, and are supported independently 65 of the platen and platen frame. The paper

is held against the platen at the printing point not only whether the latter is feeding as in letter-spacing and line-spacing, but also in case-shifting movements of the platen, the carrier constituting a shiftable 70 support actuated by the platen shifting mechanism in printing upper or lower case characters.

Having thus described my invention, I claim:

1. In a typewriting machine, the combination with a platen and platen frame, of a transparent paper-holder unconnected with the platen and frame and extending across the printing line, for maintaining the paper 80 against the platen at the printing point and leaving the writing on the entire printing line legible, and a yielding metallic support extending up in front of the platen and terminating below the printing line and attached to said transparent paper-holder.

2. In a typewriting machine, the combination with a platen and platen frame, of transparent paper-holding fingers arranged at the printing point and separated from each 90 other sufficiently to permit the imprint of the type therebetween, and a metallic device supporting the fingers yieldingly independently of the platen and platen frame, said metallic device extending in front of the 95 platen and terminating short of the printing line and attached to said fingers.

3. In a typewriting machine, the combination with a platen, of a paper-holding mechanism, including a support having open seats, 100 paper-holding fingers pivotally and removably received in the seats, and springs tending to urge the fingers toward the platen.

4. In a typewriting machine, the combination with a platen, of a paper-holding mechanism, including a recessed support, paper-holding fingers pivoted on the support, and springs carried by the fingers, the free ends of the springs being beaded to seat in the recesses in the support and urge the fingers 110 toward the platen, to hold the paper at the printing point.

5. In a typewriting machine, the combination with a platen, of a paper-holding mechanism, including a support having seats to 115 pivotally receive the fingers, springs on the fingers placed under tension by the interpolation of the seats between the fingers and the springs, respectively, to urge the fingers toward the platen.

6. In a typewriting machine, the combination with a platen and platen frame, of a label holder, including a pair of transparent paper-holding fingers adjacent the printing point to hold the label in position to be 125 printed upon, and metallic supporting means for said fingers, said supporting means extending up in front of the platen and terminating below the printing line and attached to said fingers.

7. In a typewriting machine, the combination with a platen and platen frame, of a label holder, including a pair of transparent paper-holding fingers adjacent the printing point to hold the label in position to be printed upon, the fingers extending across the printing line, and metallic supports pivoted at their lower ends and at their upper ends attached to said fingers, said supports terminating below the printing line.

8. In a typewriting machine, the combination with a platen and a shifting frame, including a rail on which the platen rides, of paper-holding mechanism for retaining the paper against the platen at the shifting printing point, and including a slidable frame, a tongue on the slidable frame, loosely received in an eye on the rail and spring-actuated transparent paper-holding fingers pivotally mounted on the slidable frame.

9. In a typewriting machine, the combination with a platen and platen-shifting mechanism for effecting the imprint of upper and lower case characters, of paper-holding mechanism for retaining the paper against the platen at the shifting printing point, including a slidable frame, a tongue carried by the frame and loosely connected with the platen-shifting mechanism, and paper-holding fingers on the slidable frame.

10. In a typewriting machine, the combination with a platen, of paper-holding mechanism including a support, paper-holding fingers removably mounted thereon, and

locking means for releasably retaining the fingers on the support.

11. In a typewriting machine, the combination with a platen, of paper-holding mechanism including a support, paper-holding fingers removably mounted thereon, and frictional locking means for releasably retaining the fingers on the support.

12. In a typewriting machine, the combination with a platen, of paper-holding mechanism including a support, paper-holding fingers removably mounted thereon, and springs engaging the support to releasably lock the fingers thereto.

13. In a typewriting machine, the combination with a platen, of transparent paper-holding fingers located on opposite sides of the printing point to hold the paper against the platen at the printing point, and metallic arms to which the fingers are attached, the arms terminating below the printing line to leave the printing thereon unobscured.

14. In a typewriting machine, the combination with a platen, of paper-holding fingers mounted independently of the platen and its frame, and resilient detents for urging the fingers toward the platen and detachably holding them against removal from the machine.

CORNELIUS B. CORCORAN.
